UNITED STATES PATENT OFFICE.

FREDERICK ALBERT TUTTLE, OF NA-AU-SAY TOWNSHIP, KENDALL COUNTY, ILLINOIS.

CULTIVATOR-SHIELD FOR CORN-CULTIVATORS.

No. 917,912.

Specification of Letters Patent.

Patented April 13, 1909.

Application filed April 18, 1907. Serial No. 368,847.

To all whom it may concern:

Be it known that I, FREDERICK A. TUTTLE, a citizen of the United States of America, residing in the township of Na-au-say, in the 5 county of Kendall and State of Illinois, have invented a new and useful Improvement in Cultivator-Shields for Corn-Cultivators, in which the following is a specification.

This invention relates to improvements in 10 shield or fender attachments for corn cultivators and its object is to provide a simple and efficient device of this character for preventing the cultivator from covering or otherwise injuring the corn.

15 A further object is to provide a shield having novel power operated means whereby it will automatically clear itself of stalks, stones, lumps of dirt, etc., accumulating therein or thereupon.

20 Another object is to provide a fender which can be run close to the corn without injury to the corn.

Another object is to provide a shield which can be conveniently adjusted to meet 25 various conditions of the corn, soil, etc.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a side elevation of the apparatus. Fig. 2 is a vertical 35 longitudinal section through the fender or shield. Fig. 3 is a plan view.

Referring to the figures by characters of reference, 1 designates parallel plates in the form of parallelograms connected in any 40 preferred manner, as by bolts 2 and having sprockets 3 journaled therebetween. These sprockets form supports and guides for an endless chain 4 one ply of which is parallel with and above the lower edges of the plates.

45 This chain has elongated pointed spurs 4^a extending therefrom and designed to project below the plates 1, 1 when in their lower-most positions.

A bolt 5 extends through the front ends 50 of plates 1 and pivotally mounted upon it is

a draw arm 6 designed to be locked at any desired angle to the plates by means of a binding nut 7 engaging the bolt. Arm 6 extends forward and is adjustably mounted in a slotted bracket 8 designed to be attached 55 to the shovel beam of a cultivator, a set screw 9 or other means being utilized for securing the arm in adjusted position within the bracket.

One of the sprockets 3 is secured to a short 60 shaft 3^a extending beyond a plate 1 and provided with a sprocket 10. An arm 11 is pivoted on this shaft and is connected by a pivot pin 12 with another arm 13. Sprockets 14 and 15 are mounted on the pin 12 and 65 rotate together, the sprocket 14 having a chain 16 thereon which drives sprocket 10, while sprocket 15 receives motion through a chain 17 from a sprocket 18 on a drive shaft 19. This shaft 19 constitutes the pivot of 70 arm 13 and is designed to be journaled on the cultivator frame. A bevel gear 20 is loosely mounted on this shaft and designed to be coupled thereto by a feathered clutch 21 actuated in any preferred manner, as by a lever 75 22. Gear 20 meshes with a gear 23 on a shaft 24 having a gear 25 thereon which receives motion from a gear 26 meshing with a gear 27 on one of the supporting wheels of 80 the cultivator.

It is to be understood that any desired number of these fenders may be attached to a cultivator and the mechanisms can be driven from either or both of the supporting wheels of the cultivator. The rotation of 85 the wheel or wheels will cause motion to be transmitted through the gears, chains and sprockets so that as the fender is drawn forward the chain 4 is actuated in the direction of the arrow, Fig. 1, and the spurs 4^a thus operate to keep clean the space between the plate.

What is claimed is:

1. A fender comprising spaced plates arranged on edge, an endless chain mounted 95 for movement therebetween and carried thereby, cleaning spurs carried by the chain, and mechanism for actuating the chain.

2. A fender comprising plates mounted on edge, an endless chain movably mounted be- 100

tween and carried by the plates, cleaning spurs carried by the chain, driving mechanism, foldable means for transmitting motion from said mechanism to the chain, and a draw arm adjustably connected to the fender.

3. A fender comprising spaced members, an endless flexible device mounted for move-

ment therebetween and carried thereby, cleaning means carried by said device, and mechanism for actuating said device.

FRED. ALBERT TUTTLE.
